UNITED STATES PATENT OFFICE.

JOHN E. GREENAWALT, OF DENVER, COLORADO.

SINTERING APPARATUS.

1,110,623.

Specification of Letters Patent. Patented Sept. 15, 1914.

Application filed June 24, 1912. Serial No. 705,495.

To all whom it may concern:

Be it known that I, JOHN E. GREENAWALT, citizen of the United States, residing at Denver, in the county of Arapahoe and State of Colorado, have invented certain new and useful Improvements in Sintering Apparatus, of which the following is a full, clear, and exact description, reference being had to the accompanying drawings, 10 forming a part hereof.

My invention has relation to improvements in sintering apparatus; and it consists in the novel details of construction more fully set forth in the specification and 15 pointed out in the claims.

In the drawings, Figure 1 is a vertical section taken longitudinally through the sintering pans on the line 1—1 of Fig. 2; Fig. 2 is a vertical section at right angles to Fig. 1 taken on the line 2—2 of Fig. 1; Fig. 3 is a top plan of the pan and one-half of the hood superposed thereover; Fig. 4 is a half side elevation and a half middle vertical longitudinal section of the pan and hood 25 superposed thereover and lowered into position thereon; Fig. 5 is a side elevation of the hood and upper edge of the pan, the hood being shown lifted off the pan; Fig. 6 is a half end view and half cross-section of the 30 hood enlarged; and Fig. 7 is an enlarged sectional detail of the hood on the line 7—7 of Fig. 3.

The present invention is directed to the construction of sintering pans in which 35 there is effected the simultaneous sinter or agglomeration of the entire charge of said pan in a single operation, the object sought being to sinter a maximum charge with the least expenditure of time and fuel. As an 40 example of such a charge, may be cited flue dust from pig-iron blast furnaces, and fine iron ores. The flue dust contains from eight to twenty-five per cent. of carbon and can be successfully agglomerated in my apparatus, the carbon supplying the necessary fuel 45 for the heat of agglomeration. It is desirable of course, to stop the operation as soon as the sintering or agglomerating of the charge is accomplished so as to retain 50 as much carbon as possible for the subsequent smelting of the charge in a blast furnace. To ores containing neither carbon nor sulfur about eight per cent. of fine coal or coke must be added to supply the carbon. A mixture of blast furnace flue dust and ores containing no combustible ingredients gives ex-

cellent practical results, the flue dust in some cases containing sufficient carbon to agglomerate or sinter three times its weight of fine iron ore containing no combustible ingredients. Other examples of charges suitable for sintering purposes may be mentioned, such as copper sulfids in fine or powdered form, and in fact any fine material containing a sufficient percentage of combustible ingredients to furnish the heat necessary to effect the agglomeration of the charge.

In the practice of my invention, the burning charge is subjected to a down-draft, the air and gases being drawn through the charge and its support by means of a suitable exhauster. It is imperative however, that before the draft fully asserts itself, the entire surface of the charge shall be ignited, 70 after which the zone of combustion will permeate the entire charge and remain commensurate with the area of ignition.

Among the objects sought is to provide means for distributing the ignition fuel (be 80 it gas, oil or powdered carbonaceous fuel) over the entire surface of the charge in planes parallel and in proximity to, such surface and at the same time supplying air or oxygen to the fuel, the said air or oxygen 85 being introduced preferably through the roof of a shallow hood temporarily placed over the charge, and forming with the walls of the pan a low ignition chamber above the charge, sealed at the sides against the influx 90 of disturbing air currents which would tend to flow over the surface of the charge and prevent the flames from contacting therewith, the roof of said hood being brought in proximity to the surface of the charge so as to 95 cause the ignition flames to instantly fill the low chamber thus formed and hold the flame against the charge and thereby insure the simultaneous ignition thereof over its entire surface, a result primarily sought by 100 the present invention.

A further object is to cause the ignition fuel to be fully ignited before responding to the draft of the exhauster whereby no unconsumed ignition fuel will enter the charge. 105

A further object is to introduce the air which supports the combustion of the ignition fuel in properly distributed volumes over the charge so that every molecule of the fuel introduced into the chamber shall 110 be ignited at one time and receive its proper complement of oxygen.

The apparatus possesses in addition, certain mechanical features the advantages of which will be fully apparent from a detailed description of the invention, which is as follows:

Referring to the drawings, 1 represents a pan or receptacle which in practice may be of any convenient size, the dimensions of that here shown being about twelve feet in length, seven feet wide and two feet deep, the side walls of the pan being provided with parallel ribs *a*, *b*, spaced a suitable distance apart to form a way or groove *c* for the reception of the ends of the grates *G*, the upper rib *a* being about ten inches below the edge of the pan, thus permitting the charging of the pan with a layer of ore or other material of substantially twelve inches in thickness. Preferably, the pan is composed of two sections bolted together through the bottom transverse flanges 2 as shown, the outer ends of the sections terminating, below the grates *G* and the charge supported thereon, in hollow trunnions 3, which thus communicate with the chamber 4 between the grates and the bottom of the pan, the trunnions being supported on wheel or roller bearings *w* as shown. The trunnions of each pan (there may be any number of pans to a plant) communicate with a box or casing 5 from which lead pipes 6, 6, to a suitable fan or exhauster *F*, the latter being driven by an electric or equivalent motor *M*. When the exhauster is in operation, the air and gases are drawn evenly through the charge and its supporting grates, into the chamber 4 and out through the hollow trunnions 3, boxes 5, pipes 6, into and out of the exhauster. The pan is freely rotatable about the common axis of the trunnions 3, (being the longitudinal axis of the pan) and when the charge thereon has been sintered the pan is rotated (by hand or otherwise) about said axis sufficiently to dump the charge onto a chute or incline 7 whence it is discharged into a car *T*.

Disposed adjacent the sides of the pan (or pans) 1 are rails *R* for the support of the wheels 8 mounted to freely rotate on roller bearings 9 at the ends of the stationary axles 10 from which the igniting hood *H* is suspended. The hood is so supported that it may be raised or lowered from and to the pan with very little effort, the preferred manner of support being by means of the U-shaped balance levers *L*, *L*, extending in opposite directions across the axles and across the length of the hood, and projecting a suitable distance beyond the ends of the hood, the free ends of the long arms of the levers being provided with piping or sleeves 11 to be grasped by the hands of the operator. The sides of the lever frames 65 are fulcrumed to the axle, being preferably

riveted to a block 12 secured (if necessary) to the axle, the short arms of the levers (or lever frames) being coupled to the hood by links 13. The weight of the levers approximately balances the weight of the hood, and an oscillation of the levers about the axes of the axles (in which oscillation the axle freely turns in its bearings in the wheels 8) produces a corresponding vertical reciprocation in the hood. When the levers *L* 75 are horizontal the hood is raised an inch or so (Fig. 5) above the plane of the upper edge of the pan (assuming of course that the pan has been rotated to a horizontal position), so that a slight oscillation of the 80 long arms of the levers *L* upwardly will depress the short arms and thus lower the hood so that the same may rest on the pan, the hood being previously wheeled directly over the pan. The engaging surfaces 85 between the hood and pan are carefully machined so that when the hood rests on the pan a tight joint or seal is formed against the influx of atmospheric cross-currents, the absence of such currents permitting the ignition flame within the igniting chamber of the hood to remain in undisturbed contact with the surface of the charge. The crown of the hood is only about six inches above the surface of the charge, and when we 90 consider that the area of this surface is substantially eighty-four square feet, the ignition chamber *C* (above the charge) is comparatively very shallow or low (Figs. 1, 2) thereby keeping the flames within it in close 95 and permanent contact with the surface of the charge. The shallowness of the ignition chamber is an important feature in the present invention as the flame of ignition readily and instantly fills the entire chamber the moment the fuel of ignition is projected into the chamber. The fuel for igniting the charge may be gas or liquid (or even powdered carbon) and is introduced into the chamber *C* through the sides 100 of the hood, through nozzles 14 leading from pipes 15 traveling with the hood, the intake ends of the pipes being coupled to flexible hose 16 leading from the main fuel supply pipe 17 and guided over sheaves *h* 110 and of sufficient length to allow for the necessary travel of the hood over the track or rails *R*, *R*. The fuel is fed under a sufficient head to cause its projection into the ignition chamber *C* across the surface of 115 the charge *m* in planes parallel and in proximity to said surface, and with sufficient momentum to overcome the suction action of the exhauster so that the fuel becomes 120 fully scattered over the surface of the charge before it can be deflected to any material extent by the currents traversing the charge 125 under the action of the exhauster.

The roof of the hood (through which the air supporting combustion of the ignition 130

fuel is admitted) is preferably constructed as shown, that is to say with a series of transverse T-bars 18 to the flanges of which is secured the outer sheet 19 having comparatively large openings or perforations *o* (one and one-quarter inch diameter). Spaced from the sheet 19 is the inner cast iron lining 20 preferably built of sections having comparatively small perforations *o'* (one-half inch diameter), the connection being effected by means of bolts 21 and spacing thimbles 22 whereby an air jacket 23 is formed between the outer sheet and its lining, said jacket keeping the roof of the hood comparatively cool. The vertical walls of the hood are formed preferably of Z-bars *t* as shown, the corners of the hood being provided with brackets 24 with central depressions so as to pass around the lower halves of the axles 10 when the hood is raised to its highest position to clear the pan (Fig. 5). Traveling over the pan (or series of pans) is a trolley charging car 25 which charges the pans when necessary, this feature not being here entered into in detail as the car forms subject-matter for a separate application. It is merely illustrated here to show its application to the pans. Features of construction here illustrated but not alluded to are well understood by the practical engineer and by those skilled in the art, and require no detailed description in the present connection.

The operation of the invention will now be readily understood. A pan having been charged from the car 25 and carefully leveled off, (the manner of filling the car not being here entered into because well understood in the art), the hood is pushed over the pan and then lowered into operative position therewith as already described, an air tight joint being formed between the machined engaging surfaces. As the hood is brought into position the exhauster is started and the operator inserts a lighted torch or flame into the chamber C through a torch hole 26 (normally covered by a swinging plate 27) and opens the valve V (Fig. 1) of the main fuel-supply pipe 17 whereupon the fuel is projected across the charge and in planes substantially parallel to the surface thereof, the charge reaching as already stated to the upper edge of the pan and forming in effect the bottom of the ignition chamber C. The momentum of the fuel streams projected across the charge through the nozzles 14 prevents any material deflection thereof by the currents drafted through the charge by the exhauster, and hence no fuel is lost by being drawn prematurely into the charge. The gases of combustion, and the roaster gases and air (percolating through the roof of the hood to supply the oxygen for the fuel and combustible elements of the charge) are how-

ever drawn through the charge and the slots of the grates, and into, through and out of the chamber 4 as already described. The low roof of the ignition chamber C not only insures an instantaneous filling of this chamber with flame which forms a blanket over the charge, but holds the flame blanket in close contact with the entire surface of the charge, any disturbance of such contact being impossible owing to the absence of interfering cross air currents, which are effectively cut off by the seal between the hood and the pan. It follows therefore that under the action of the exhauster the zone of combustion after the surface of the charge is once ignited, will permeate the entire charge and be maintained commensurate with the original area of ignition. In practice the hood once deposited over a pan may rest there until moved over another pan, or it may be removed after the charge is once well ignited, the exhauster drawing the zone of combustion through the charge after the removal of the hood. Of course, to remove the hood, the operator simply depresses the levers L which raises the hood sufficiently to clear the pan, after which the hood may be readily wheeled out of the way or over the next pan of the series. The charge being fully treated, the operator stops the exhauster, turns the pan on its axis through an angle of approximately one hundred and eighty degrees and dumps the sintered mass onto the chute 7 whence it is received by the car T. Obviously, the fuel supply is cut off by closing the valve V the moment the charge is fairly ignited, in cases of charges having sufficient combustible elements to supply the heat of incipient fusion, in which cases the hood may be removed after ignition of the charge. In treating ores having no appreciable quantities of combustibles, the hood is allowed to remain and the fuel supplied through the nozzles 14 to furnish the necessary heat and air for purposes of oxidation. In the latter cases of course, the ultimate object of the treatment need not necessarily be to secure a sintering or agglomerating effect, but to recover values.

In order to prevent the fine material *m* of the charge from clogging and destroying the grates, a layer of coarse porous material *m'* reasonably free from combustible matter, and from one-quarter to one inch in thickness is first deposited on the grates, said coarse and comparatively incombustible layer not only preventing the fine top layer from being drawn through the slots of the grates, but being itself susceptible of ready removal from the grates. This coarse layer too permits an even flow of gases through all portions of the grate surface thereby producing a uniform product. The coarse inert layer forms in effect a porous hearth on which the main charge to be sintered is

treated. The charge as a whole is of course, properly mixed and moistened before being deposited on the grate as well understood in the art.

5 Obviously, the apparatus need not be restricted specifically to the "sintering" of ores. In treating sulfid ores for example where the object sought is to remove a maximum amount of sulfur, it is desirable to pass 10 the air and gases through the charge just as long as any sulfur continues to burn; or where the sulfid ore is treated for matte making the gases are drawn through the charge until just enough sulfur remains in 15 the charge to make it available for this specific purpose, unless the fineness of the charge requires the process to be continued to the point of sintering. In treating iron ores for 20 the blast furnace which do not contain sulfur in injurious quantities, it is desirable to stop the action as soon as the sintering result has been attained, for by this method of procedure considerable carbon can be retained in the sintered material which becomes available in the subsequent blast furnace reduction process. These matters are 25 here mentioned to make it clear that the apparatus herein is available for the treatment or roasting of any ore or material, be 30 the process carried to the point of sintering or incipient fusion or not.

Having described my invention, what I claim is:—

1. In a sintering apparatus, a receptacle 35 having a perforated support for the charge, an exhauster for drafting gases through the charge and through the perforated support, igniting means adapted to be superposed over the charge, and means for projecting 40 the ignition fuel across the surface of the charge in paths substantially parallel to said surface and transverse to the flow of the gases drafted through the charge whereby the entire surface of the charge is simultaneously 45 ignited.

2. In a sintering apparatus, a receptacle having a perforated support for the charge, an exhauster for drafting gases through the charge and through the perforated support, 50 igniting means adapted to be superposed over the charge, and means for projecting the ignition fuel across the surface of the charge in paths substantially parallel and in proximity to, said surface and transverse to 55 the flow of the gases drafted through the charge, whereby the entire surface of the charge is simultaneously ignited.

3. In a sintering apparatus, a receptacle having a perforated support for the charge, 60 an exhauster for drafting gases through the charge and through the perforated support, a hood positioned over the receptacle and forming a low ignition chamber above the charge sealed at the sides against the influx 65 of atmospheric cross-currents, and means for

filling said chamber with flame to cause a substantially simultaneous ignition of the entire surface of the charge.

4. In a sintering apparatus, a receptacle having a perforated support for the charge, 70 an exhauster for drafting gases through the charge and through the perforated support, a hood positioned over the receptacle and forming a low ignition chamber over the charge sealed at the sides against the influx 75 of atmospheric cross-currents, means for projecting streams of ignition fuel through the walls of the hood directly over, and in planes substantially parallel to, the surface of the charge and transverse to the general direction of flow of the gases drafted through the charge; and means for admitting combustion-supporting gases through the roof of the hood to supply oxygen to the ignition fuel. 80

5. In a sintering apparatus, a receptacle having a perforated support for the charge, an exhauster for drafting gases through the charge and its support, igniting means adapted to be superposed over the charge, 90 and means for effecting an even distribution of ignition fuel over the entire surface of the charge to bring about a simultaneous ignition of the charge over said surface. 95

6. In a sintering apparatus, a receptacle having a perforated support for the charge, an exhauster for drafting gases through the charge and its support, a hood positioned over the receptacle and forming therewith an ignition chamber above the charge sealed 100 at the sides against influx of cross air currents, means for distributing ignition fuel over the surface of the charge, and means for feeding air in distributed volume through the roof of the hood for igniting 105 the fuel simultaneously over the entire surface of the charge.

7. In a sintering apparatus, a receptacle having a perforated support for the charge, an exhauster for drafting gases through the charge and its support, means for generating an igniting flame simultaneously over the entire surface of the charge, and means for holding said flame in contact with said surface. 115

8. In a sintering apparatus, a receptacle having a perforated support for the charge, an exhauster for drafting gases through the charge and its support, and an igniting hood having a roof positioned in close proximity 120 to the charge and forming therewith a low ignition chamber over the charge.

9. In combination with a receptacle holding a charge to be treated, a hood adapted to be positioned over the charge, means for introducing ignition fuel through the hood over the charge, the roof of the hood being provided with an outer perforated shell and an inner perforated lining spaced therefrom. 125 130

10. In combination with a receptacle holding a charge to be treated, an igniting hood adapted to be moved into position over the receptacle, and balancing members coupled 5 to the hood for respectively raising and lowering the hood from and to the receptacle.
11. In combination with a receptacle holding a charge to be treated, an igniting hood provided with supports adapted to be moved 10 over the receptacle, and balancing levers carried by said supports and coupled to the hood for raising and lowering the same.
12. In an apparatus of the character described, an igniting hood, wheel-axles for 15 moving the same disposed at each end of the hood, levers coupled to the axles and having their long lever-arms extending over the hood in opposite directions, the short arms of the levers being linked to the adjacent ends 20 of the hood, the levers serving as balancing members, for the hood.
13. In an apparatus of the character described, an igniting hood, axles therefor, wheels on said axles, balance levers ful- 25 crumed about the axes of the axles and extending in opposite directions over the hood, and links pivoted to the ends of the hood and to the adjacent lever-arms of the levers.
14. In a down-draft sintering pan, a shal- 30 low hood forming with the pan a low igni- tion chamber above the charge in the pan, and means for filling said chamber with flame, whereby the zone of ignition sim- 35 taneously permeates the entire charge under the action of the draft.
15. In an apparatus of the character de- 40 scribed, an igniting hood provided with an outer perforated sheet, and an inner per- forated lining spaced therefrom and form- ing an air jacket therewith.
16. A sintering apparatus comprising a receptacle rotatable about a fixed axis and having an upper compartment for the charge and a compartment below the charge com- 45 municating with the upper compartment 50 through the charge and its support, hollow trunnions leading from the lower compartment and disposed about the rotation axis of the receptacle, an exhauster communicating with the lower compartment through the 55 hollow trunnions, a hood adapted to be tem- porarily placed over the charge and forming above the latter a shallow ignition chamber, and means on said hood for supplying an inflammable mixture adapted to be drawn 60 toward the surface of the charge, and the flame of the mixture held against said sur- face, the gases being evenly drawn through the charge by the exhauster and a zone of combustion simultaneously maintained 65 throughout the entire charge.
17. In a sintering apparatus, a receptacle having a perforated support for the charge, an exhauster for drafting gases through the charge and its support, an ignition chamber 70 above the charge, means for distributing within the chamber ignition fuel over the surface of the charge, and means for feeding air in distributed volume for igniting the fuel simultaneously over the entire surface 75 of the charge.
18. In a sintering apparatus, a receptacle having a perforated support for the charge, an exhauster for drafting gases through the charge and its support, an ignition chamber 80 above the charge, means for distributing within the chamber ignition fuel over the surface of the charge, and means for feeding air in distributed volume through the roof of the chamber for igniting the fuel sim- 85 taneously over the entire surface of the charge.

In testimony whereof I affix my signature,
in presence of two witnesses.

JOHN E. GREENAWALT.
